PACKAGE FOR RADIO TUBES AND
THE LIKE

George F. Bart, Long Island City, N. Y.

Application May 13, 1935, Serial No. 21,094

11 Claims. (Cl. 229—39)

The present invention relates to a package for radio tubes, incandescent bulbs, and the like, and a carton comprising the outer covering of a package. The improvements are designed to provide 5 a holder wherein the packaged object may be firmly protected, yet may be inspected by the purchaser thereof. A primary object, among others, is to provide a one-piece outer covering which may be manufactured and shipped in flattened condition and which may be assembled at the manufacturer's plant without the necessity of expensive assembling machinery.

Another object is to provide means whereby a radio tube may be packaged in such a manner that 15 the purchaser may readily perceive that a tube has not been substituted or used to any extent and whereby it may nevertheless be ascertained that the radio tube is in good working condition before the purchase is consummated.

Another object of the invention is to provide 20 means whereby incandescent bulbs or the like may be packaged in such a manner that the purchaser may readily ascertain that a bulb has not been substituted or used to any extent and yet may 25 likewise ascertain that the bulb is in good working condition.

A further object of the improvements is to provide 30 a carton within which a bottle, or other container, or a package may be positioned, the carton comprising means for assembling without the necessity for complicated assembling mechanism, and which cannot be tampered with without leaving evidence of tampering.

A further object of the improvements is to provide 35 a carton suitably adapted to accommodate fragile articles such as incandescent bulbs, radio tubes and the like, positioned within packing means such as described and claimed in the patent issued to Morris Koppelman, No. 1,986,344, on 40 January 1, 1935, whereby reduction in breakage of packaged articles is accomplished.

Other objects and advantages of the present 45 improvements will be apparent to those skilled in the art upon reference to the accompanying description and drawing in which

Fig. 1 is a plan view of a blank for the outer covering of my improved package or the carton therefor;

Fig. 2 is a view in perspective of an inner packing or protective sheath having a radio tube associated therewith, the sheath being in accordance with the disclosure of the heretofore mentioned patent to Morris Koppelman;

Fig. 3 is a perspective view of the radio tube

and sheath sealed within the assembled carton of Fig. 1;

Fig. 4 is a plan view of a modified form of blank embodying the features of my invention;

Fig. 5 is a perspective view of the blank of Fig. 4 in partially assembled condition; and

Fig. 6 is a partial perspective view of the carton of Fig. 5 showing the assembled tamper-proof sealing means.

In the embodiments illustrated herein the outer covering or carton of the package comprises a single sheet of carboard or suitable equivalents, and manufactured from a larger sheet of cardboard in any suitable blank-forming machinery. Each blank embodies the same generic features, the 10 differences between the blank of Fig. 1 and the blank of Fig. 4 comprising specific elements of which the purposes will presently appear.

The blank of Fig. 1 comprises a main panel 10, preferably slightly longer than the article to be 20 packaged. Contiguous thereto is a side panel 11 and an opposite side panel 12 to which is attached a fourth panel 13. Each of the panels 10, 11, 12 and 13 are rectangular and of the same dimensions. To the free edge of side panel 11 is attached a gummed flap 14 by means of which a tubular blank may be formed by adhering the flap 14 to one surface of the free end of panel 13.

Other suitable means may be provided whereby a tubular member, rectangular in cross-section, may be formed. Attached to adjacent ends of one of the panels, in this instance panel 10, is a top-forming panel 15 having side flaps 16 and 17 and an extension 18. The top panel 15 is folded to 30 cover the open end of the tubular blank and the side flaps 16 and 17 are preferably tucked inside the end of the tubular blank without being adhered or otherwise secured thereto, thereby substantially closing the end of the blank and bracing 40 the structure. The extension 18, which may have a decorative outline as illustrated, is folded upon the outer surface of the tubular blank. The extension is preferably slightly longer than one half the length of the panels, thereby extending to 45 slightly beyond the center line of the tubular blank. The opposite end of the same panel is provided with a bottom-forming panel 20, having side flaps 21 and 22 which are preferably tucked within the tubular blank as previously described

and an extension 23, preferably of the same shape and dimensions as the extension 18. As seen in Fig. 3, the extensions 18 and 23 will overlap when folded along the surface of the tubular blank op- 50 55

posite to the panel to which the extensions are attached.

The inner protective sheath, as described and claimed in the aforementioned patent, is preferably formed by a pulp-sucking or moulding process in suitable machinery well-known to the trade. The sheath comprises a single blank having a plurality of sections 30, 31, 32 and 33, of substantially the same length as the panels of the carton, hinged at 34, 35 and 36, whereby the sections may be folded into an open-end tubular sheath with the end edges of the blank meeting at 37. Each section is preferably curved in cross-section so as to provide inwardly arched sides of the tubular sheath. The sections, however, may be formed of uniplanular material, the width of each being greater than the width of a panel of the outer cover, whereby in order to force the sheath into the carton the sides must be inwardly arched. However, it is apparent that the preformed arched sections are best for many reasons.

In packing certain articles the arched sections may be provided with outwardly protruding, convex portions 40 suitably designed and of such dimensions as to embrace the surfaces of an article accommodated therein, such as a radio tube, illustrated in Fig. 2. The convex portions 40 embrace the surface of the radio tube and substantially prevent longitudinal movement thereof, whereby the ends of the tube are prevented from knocking against the ends of the outer covering. Likewise, the sections are preferably such that a plane surface across adjacent hinges, as from 34 to 35, will pass above the uppermost extent of the interposed convex portion 40 whereby the sides of the enclosed article will be prevented from knocking against the side panels of the outer covering.

40 The sheath is preferably formed of semi-rigid, but nevertheless resilient material. This is particularly true of sheaths manufactured from moulded pulp. It can be seen that pressure upon either end of the enclosed article will move it longitudinally to project beyond the limits of the sheath. In order that this may be accomplished while the sheath and article are sealed within the outer cover, there is provided a small opening 41 in the top-forming panel 15 and a large opening 42 in the bottom-forming panel 20. A person's finger may be thrust through opening 41 to apply pressure to the top of the radio tube or other article and to move the radio tube longitudinally to project the contacts thereof through the opening 42.

The outer cover is assembled into a tubular open-ended blank and the associated article and inner sheath are slid therein through either end, the corners of the carton embracing the hinges 60 of the sheath. The top and bottom panels are then folded to cover the ends and the extensions 18 and 23 are overlapped as seen in Fig. 3. Sealing of the package is accomplished by the simple operation of driving a single eyelet, 65 staple or other fastening means 45 through the overlapped ends of the extensions, or otherwise unattachably uniting the ends. The carton cannot be opened to withdraw the article without there being evidence of the seal having been tampered with. If desired, the sealing member 45 may be such that it cannot be removed without completely removing the ends of the extensions 18 and 23 so that they no longer overlap.

A prospective purchaser may thrust the contacts of a radio tube through the bottom open-

ing, which is large enough for that purpose but smaller than the largest portion of the tube, and the sealed radio tube may be placed in a testing circuit to determine its condition. The resilient walls of the sheath normally retain the radio tube within the confines of the carton and will so retain the radio tube after it has been tested and returned to its normal position.

It is to be appreciated that an incandescent bulb may be tested in a similar manner. Likewise, the enclosed article may be of some other nature such as a container having a sealed cap, the sealed cap being extended through the opening 42 for inspection thereof.

In the modification of Figs. 4, 5, and 6 the objects and advantages of the previously described modification are embodied. The blank comprises a main panel 50 having contiguous panels 51 and 52 of the same dimension, from which three sides of an open-ended tubular blank may be formed. In this instance the fourth side of the tubular blank is provided by a panel 53 fixed to panel 51 and a panel 54 fixed to panel 52, panel 53 being placed beneath panel 54 with projections 55, 56 and a locking tongue 57 preventing the panels from sliding beyond each other. As seen in Fig. 5, the locking tongues 55 and 56 may be placed on top of the panel 54, while an extended portion of panel 54 will be placed on top of panel 53, thereby interlocking the two panels, the locking being insured by turning locking-tongue 57 upward through a slot 58 in panel 53. The ends of the tubular blank are closed by panels 60 and 61 extending from opposite ends of panel 50 provided with bracing flaps 62, 63 and 64, 65, respectively. The outer ends of the panels are provided with extensions 66 and 67 similar to panels 18 and 23 of Fig. 1. In this instance the extensions are provided with slots 68 and 69 respectively which register when the extensions are overlapped, as previously described. The registered slots are so placed as to embrace the upwardly projecting locking tongue 57 (Fig. 5). One of the extensions (66) is provided with a tab 70, adjacent slot 68 and extending toward the edge of the carton, upon which the locking tongue may be folded, as seen in Fig. 6, and thereupon the carton may be sealed by passing a sealing member 71 through the locking tongue and the tab. The carton cannot be opened without leaving evidence of tampering and does not require extensive sealing mechanism to achieve this result.

The carton may be provided with openings similar to openings 41 and 42 of the previously described form. This form of carton, however, is preferably to be made in larger sizes to accommodate larger articles such as quart bottles and the like. One or more of the panels may be provided with openings 75 through which a portion of the enclosed article may be viewed. The article may be associated with a protecting sheath, as previously described.

I have herewith described and illustrated two embodiments of my present invention. It will be apparent from the following claims that the true scope of my invention is not to be determined by the specific details disclosed, but by the breadth and scope of the claims themselves. Various other modifications will be apparent to those skilled in the art, and I claim such modifications as my invention in so far as permitted by the statutes and rules applicable thereto.

I claim:

1. A carton comprising, a tubular blank, end

- 5 closures for said tubular blank attached to opposite edges thereof and adapted to be folded over the open ends to form a substantially complete enclosure, and a seal comprising extensions of said end closures adapted to overlap along the outer surface of the carton and means to unite said extensions to each other and to the blank at their overlapped ends.
- 10 2. A carton comprising, a tubular blank comprising attached panels, end closures for said tubular blank attached to one of said panels and adapted to be folded over the ends of said tubular blank to form a substantially complete enclosure, and a seal for the carton comprising an extension of each of said end closures adapted to overlap along the outer surface of the one of said panels opposite the one to which said end closures are attached and means to unite said extensions to each other at their overlapped ends, said 15 means comprising a locking tongue projecting from the surface of the adjacent panel, said extensions having registering slots through which said tongue may be passed to form a part of the seal.
- 20 25 3. A carton comprising, a tubular blank comprising attached panels, end closures for said tubular blank attached to one of said panels and adapted to be folded over the ends of said tubular blank to form a substantially complete enclosure, and a seal for the carton comprising an extension of each of said end closures adapted to overlap along the outer surface of the one of said panels opposite the one to which said end closures are attached and means to unite said extensions to each other at their overlapped ends, said means comprising a locking tongue projecting from the surface of the adjacent panel, said extensions having registering slots through which said tongue may be passed to form a part of the seal, and a tab projecting from one of said extensions to which the locking tongue may be united after passing through said slots.
- 40 45 4. A carton comprising, a tubular blank comprising attached panels, end closures for said tubular blank attached to one of said panels and adapted to be folded over the ends of said tubular blank to form a substantially complete enclosure, and a seal for the carton comprising an extension of each of said end closures adapted to overlap along the outer surface of the one of said panels opposite the one to which said end closures are attached and means to unite said extensions to each other at their overlapped ends, said means comprising a locking tongue projecting from the surface of the adjacent panel, said extensions having registering slots through which said tongue may be passed to form a part of the seal, and said end closures having side flaps thereon adapted to be tucked into the open ends 50 of the tubular blank.
- 55 60 5. A package for fragile articles having a major dimension and a reduced end, such as radio tubes, comprising a permanently sealed outer enclosure, an inner sheath comprising an open ended tubular blank consisting of inwardly arched sections embracing the major dimensioned portion of said article, said outer enclosure having an opening through one end of sufficient size to allow passage of said reduced end of the article.
- 65 70 6. A package for fragile articles having a major dimension and a reduced end, such as radio tubes, comprising a permanently sealed outer enclosure, an inner sheath comprising an open ended tubular blank consisting of inwardly arched sections embracing the major dimensioned portion of said article, said outer enclosure having an opening through one end of sufficient size to allow passage of said reduced end through said first opening.
- 75 80 7. A package for fragile articles having a major dimension and a reduced end, such as radio tubes, comprising a permanently sealed outer enclosure, an inner sheath comprising an open ended tubular blank consisting of inwardly arched sections embracing the major dimensioned portion of said article, each of said arched sections being provided with convex portions shaped to embrace the surface of said article, said outer enclosure having an opening through one end of sufficient size to allow passage of said reduced end of the article.
- 85 90 8. A package for fragile articles having a major dimension and a reduced end, such as radio tubes, comprising a permanently sealed outer enclosure, an inner sheath comprising an open ended tubular blank consisting of inwardly arched sections embracing the major dimensioned portion of said article, each of said arched sections being provided with convex portions shaped to embrace the surface of said article and the material of said sheath being sufficiently flexible to permit movement of said article, said outer enclosure having an opening through one end of sufficient size to allow passage of said reduced end of the article.
- 95 100 9. A package for fragile articles having a major dimension and a reduced end, such as radio tubes, comprising a permanently sealed outer enclosure, an inner sheath comprising an open ended tubular blank consisting of inwardly arched sections embracing the major dimensioned portion of said article, each of said arched sections being provided with convex portions shaped to embrace the surface of said article and the material of said sheath being sufficiently flexible to permit movement of said article and sufficiently rigid normally to prevent movement of said article, said outer enclosure having an opening through one end of sufficient size to allow passage of said reduced end of the article.
- 105 110 10. A package for fragile articles comprising a sealed carton and an inner sheath therefor, said sheath resiliently embracing an article, said carton having openings at its opposite ends of a size less than the maximum diameter of said article, said carton and sheath being substantially equal in length and longer than said article.
- 115 120 11. A package for fragile articles comprising a sealed carton and an inner sheath therefor, said sheath resiliently embracing an article, said carton having openings at its opposite ends of a size less than the maximum diameter of said article, said carton and sheath being substantially equal in length and longer than said article, said sheath normally retaining said article against movement but being sufficiently resilient to permit movement whereby a portion of said article may be projected through one of said openings.
